JOSEPH ALEXANDER MAYERS, OF BROOKLYN, NEW YORK.

AUTOMATIC THERMOSTATIC FUEL-CONTROLLING DEVICE.

1,202,869.

Specification of Letters Patent. Patented Oct. 31, 1916.

Application filed April 28, 1915. Serial No. 24,479.

To all whom it may concern:

Be it known that I, JOSEPH ALEXANDER MAYERS, a citizen of the United States, and resident of Brooklyn, county of Kings, and State of New York, have invented certain new and useful Improvements in Automatic Thermostatic Fuel-Controlling Devices, of which the following is a specification.

This invention relates to automatic thermostatic fuel-controlling devices; the objects of the invention being to provide an automatic fluid seal valve for controlling the flow of either liquid or gaseous fuels which is operated by thermostatic means; which is instantaneous in its action; and which may be set to alternately turn the fuel on and off, at predetermined degrees of temperature.

The foregoing and other objects I attain by employing four chambers which are inclosed against the atmosphere and connected with each other in series; an inclosed column of air expansible element; a looped transmission-tube, of substantially inverted U-shaped contour; a heat-generating burner, a pilot-burner, and an inlet and outlet fuel pipe; and mercury contained within the said chambers, all as will be hereinafter fully described and specifically set forth in the annexed claims.

In the accompanying drawings forming part of this specification, Figure 1 is a longitudinal sectional view illustrating my invention; Fig. 2 a sectional plan view taken on the line 2-2 of Fig. 1; and Fig. 3 is a cross section taken on the line 3-3 of Fig. 1, showing a detail of my invention, drawn on an enlarged scale.

In the example of my invention shown in the accompanying drawings and particularly illustrated by Fig. 1, the apparatus is shown in a position supplying gas to a burner. A and B, indicate respectively chambers which are separated from each other by a partition C; and said chambers communicate with each other by means of a looped transmission-tube D, of substantially inverted U-shaped contour, which embodies the parallel legs or channels 1 and 2, which are extended vertically, and the lateral loop 3, which is extended horizontally. Said chamber A contains at its bottom enough mercury a to reach to the bottom of the leg 1 of the transmission-tube D, and at least half as much more mercury as will fill the transmission-tube. The chamber A

communicates with a thermostatic-chamber E, containing an air thermostatic medium and having its upper section e, placed in contact with or near the object to be heated in such a manner as to have its contents affected by the temperature of the object to be heated. For example, in the case of a boiler, as M, shown in Fig. 1, it is extended into said boiler.

The chambers A and B, respectively contain a quantity of mercury indicated by a and b, and the transmission-tube D has one leg dipping in the mercury a in chamber A, and the other reaching to the top of the mercury b, in chamber B, and the lateral extension or part 3 of said transmission-tube is located outside of the chambers A and B, and bent laterally. The said transmission-tube is composed of pliable or malleable metal, and its loop 3 is adapted to swing, for changing its elevation, by bending, said bending operation being accomplished by turning the screw 4, through the post 5, said screw being swiveled at 6, and connected with the free end of bend or loop 3, of the transmission-tube, by means of the eye 7. A block 8 contacts with the tube D, and the post 5 is located adjacent thereto, said post forms a rigid bearing through which the screw 5 is threaded, and it and the block 8 form bearing surfaces on which the transmission-tube D, can be bent without risk of breaking same at the points where the vertical legs thereof respectively emerge from the lid or top wall of the chambers A and B. This mechanism is for the purpose of raising or lowering the elevation of the transmission-tube to vary the height or distance the mercury is required to travel.

The chamber B is supplied with mercury b, up to the level of the bottom of the leg 2, of the transmission-tube which is within said chamber B. Communicating with the chamber B, by means of an opening 9, through the partition d, is a chamber F, which is adjacent to a chamber G, and separated therefrom by a partition g; a laterally contracted and vertically elongated passage-way II leads downwardly from the chamber F and communicates at its bottom with an opening h, leading to a passage-way I, which leads upwardly into the chamber G; these passage ways are elongated to prevent thermostatic communication between chambers F and G, due to any extremes of temperature; mercury i, is placed

- in the chambers F and G, in sufficient quantity to have its upper surface normally below the bottom of the pipe J, to permit gas to leave chamber G through said pipe J.
- 5 Leading into chamber G, from any source of fuel-supply is a pipe 10, for supplying fuel to the burners K and L. The pilot-burner L, being connected by the tube 11, with the fuel supply pipe 10 before the latter enters chamber G and ahead of a valve 12, which is a burner shut-off valve of ordinary type; said tube 11 is also provided with a shut-off valve 13.
- To illustrate the operation of my invention, let us assume that fuel shall be turned on full at 130° and kept full on until the object to be heated reaches 150°. To set the apparatus for this condition, disconnect the upper part of chamber E, viz.—the section 20 *e*, from the lower part, at the joint *f*, closing valves 12 and 13. Bend the external portion or loop 3 of the transmission-tube upward until its top is elevated above its bottom opening and at a height equal to a column of mercury that will sustain a pressure equal to that caused by the raising of the temperature of the thermostatic medium in the upper part of chamber A from 130° to 150°. Hot water is then placed in the 25 boiler at 130°, or the water is brought to that temperature by a temporary heating device, in order to bring the medium in the thermostatic member to 130° temperature. Now connect the lower section of the thermostatic-chamber E with the upper section *e*, by making up joint *f*. Now open valve 13 and light the pilot-light at the burner L, and then open valve 12, when gas will immediately flow with full volume through 30 the pipe 10 down to the bottom of the tube J, and through to the burner K, and will be ignited by the pilot light. A full volume of gas will continue to flow to the burner, and when the temperature of the object to be heated gets just past 150°, or just over 20° above the temperature from which it was raised, the mercury in the leg 1 of the transmission-tube D, will be driven upward through it and across the loop 3, and downward through the leg 2, into chamber B, and as the mercury which is forced 35 from A to B is so small an amount—only sufficient to half fill the transmission-tube—it will spread out in the bottom part of chamber B and cause only a very shallow seal in B. The leg 2, now acts as an outlet from the chamber A, for the thermostatic medium; the compressed medium in said chamber A, under the thermostatic pressure, will rush instantaneously through the transmission-tube, from chamber A into chamber B and will break through the thin seal in B, following through chamber B to chamber F, through the opening 9, forcing the mercury in chamber F down the passage way

H, through the bottom opening *h*, and upward through the passage way I to chamber G, and far enough above the bottom, or fuel-inlet of the tube J, to seal it, whereby said mercury immediately forms a seal and prevents further flow of fuel to the burner K.

As the temperature of the heated water drops the thermostatic medium in the chamber E is contracted, causing a tendency to vacuum, which pulls the mercury in chamber B, up leg 2 of the transmission tube D, until the vacuum gets just greater than that caused by the dropping of pressure from 150° to 130°, or a loss of temperature just above 20° from its maximum temperature of 150°, when the mercury is pulled across the transmission-tube, down leg 1, and is deposited in chamber A, which then permits the contraction of the thermostatic medium in chamber E to break the slight seal then formed in chamber A and to pull the medium back from chamber B, and therefore also from chamber F, raising the mercury in chamber F and dropping the mercury suddenly below the opening or lower end of the tube J, in chamber G, again permitting gas to supply the burner.

It will be noted that while the temperature of the thermostatic medium in E is rising or falling between the predetermined temperatures for which the appliance is set, that there is a gradual and minute rise or fall in the mercury level in chamber G, due, in the first case, to the addition to the medium in chamber B of a volume of the medium equal to the volume in half the transmission-tube D; and in the latter case, to the exit of an equal quantity of mercury leaving chamber B through the transmission-tube D. The preliminary effects however are so minute, both in the rise and fall of the mercury in chamber G, as compared with the ultimate major instantaneous movement in chamber G, that they are negligible, neither turning any gas off or on. It will be noted that the area of the chamber F is considerably larger than the chamber G, thus only a slight lowering of the mercury in said chamber F causes a greatly multiplied and hence very rapid upward movement of the mercury in chamber G.

Although I have shown the top of the transmission-tube outside of the chambers A and B, it may be placed wholly within the two chambers, one leg to a chamber, and the connecting portion of the legs of the transmission-tube, otherwise the bend therein, passing through the walls separating the two chambers A and B, but such a connection would not permit the changing of the elevation of the free end of the transmission-tube without removing parts of the walls of the chambers in order to get at same. It is also possible to make all of the walls of each chamber entirely separate

from the others and connecting the necessary openings with piping, or other details of construction might be employed without departing from the spirit and scope of my invention. There may be various arrangements of inlet and outlet openings for fuel in chamber G, such as a divided septum, or one or more openings depending in chamber G, etc., and any of these may be used, as 10 any opening presented to the rise and fall of the mercury in chamber G will be closed or opened by said mercury.

Having thus described my invention, what I claim as new, and desire to secure by Letters Patent, is:

1. A thermostatic device comprising adjacent chambers closed to the atmosphere and containing respectively a column of mercury in their bottom parts, and a thermostatic chamber closed to the atmosphere and containing an expansible medium, said thermostatic chamber communicating with one of said mercury-containing chambers; fuel inlet and outlet pipes arranged in one 25 of said mercury containing chambers; a transmission-tube of substantially inverted U-shape embodying a laterally bent loop and vertical legs depending therefrom which extend respectively into two of said 30 mercury-containing chambers and means for bending said loop, whereby the elevation of its free end may be varied for regulating the travel of mercury therethrough and comprising a bearing-block, a post and 35 a screw threaded through said post, said screw having a swiveled eye engaging said loop, substantially as shown and described.

2. In a thermostatic device, the combination, with a thermostatic-chamber closed to 40 the atmosphere and containing an expansible medium, a chamber having an opening leading into said thermostatic-chamber and closed to the atmosphere and containing mercury, and a chamber adjacent to said 45 last named chamber and also containing mercury and closed to the atmosphere, a fuel inlet pipe and a fuel outlet pipe disposed in one of said chambers, of a looped transmission-tube of substantially inverted 50 U-shape connecting said mercury-containing chambers and adapted for transferring mercury alternately to and from said chambers and manually operable means for regulating the movement of the mercury from said 55 chambers to the chamber containing the inlet and outlet pipes, substantially as shown and described.

3. In a thermostatic device, the combination, with a thermostatic chamber closed to 60 the atmosphere and containing an expansible medium, a chamber communicating with said thermostatic-chamber and closed to the atmosphere and containing mercury, chambers adjacent to said last named chamber 65 and also containing mercury and closed to

the atmosphere; fuel inlet and outlet pipes arranged in one of said chambers, of a transmission-tube comprising two vertical legs and a lateral loop connecting them, said legs depending from said loop into the first 70 named mercury-containing chambers establishing communication between them, said transmission-tube composed of pliable material whereby the free end of its loop may be raised and lowered for varying its elevation, substantially as shown and described and means engaging the lateral loop for regulating the passage of the mercury through the transmission tube to the other of said chambers.

4. In a thermostatic fuel-controlling device, the combination, with a closed thermostatic-chamber containing expansible medium, two closed transmission-chambers containing mercury, one of which communicates with 80 said thermostatic-chamber, and two adjacent chambers which communicate with each other, and fluid-sealing means within all of said chambers, all of said chambers closed to the atmosphere, and a looped transmission 85 tube connecting the transmission chambers whereby the sealing means may be transferred from one to the other, and, a fuel-inlet pipe, and a fuel outlet pipe, substantially as shown and described.

5. In a thermostatic fuel-controlling device, the combination, with a closed thermostatic-chamber containing an expansible medium, two transmission-chambers one of which communicates with said thermostatic 90 chamber, and two chambers closed to the atmosphere and communicating with each other and with the said transmission chamber which does not communicate with said 95 thermostatic chamber, all of said chambers containing mercury in their bottom parts; of a transmission-tube of substantially inverted U-shape and comprising means for communication between said transmission-chambers whereby mercury may be passed back and forth to and from said chambers, substantially as shown and described, a fuel inlet pipe and a fuel outlet pipe and means for regulating the passage of the mercury through the said transmission tube to said 100 fuel outlet pipe.

6. In a thermostatic fuel-controlling device, the combination, with a closed thermostatic chamber containing an expansible medium, and two transmission-chambers one of which communicates with said thermostatic chamber, and two chambers closed to the atmosphere and communicating with each other and with the said transmission-chamber which does not communicate with 105 said thermostatic chamber, all of said chambers containing mercury in their bottom parts, and a transmission-tube of substantially inverted U-shape adapted for transferring mercury back and forth to and 110

- from said transmission chambers; of a fuel-inlet pipe, a fuel outlet pipe, a heat generating burner, a pilot burner, and a heated object, substantially as shown and described.
- 5 7. In a thermostatic fuel-controlling device, the combination, with a closed thermostatic-chamber containing an expansible medium, two transmission-chambers one of which communicates with said thermostatic chamber, and two chambers closed to the atmosphere and communicating with each other and with the said transmission chamber which does not communicate with said thermostatic chamber, all of said chambers
- 10 15 containing mercury in their bottom parts, one of said two last named chambers being larger in area than the other; of a trans-

mission-tube of substantially inverted U-shape and comprising means for communication between said transmission-chambers 20 whereby mercury may be passed back and forth to and from said chambers, substantially as shown and described, fuel inlet and outlet pipes communicating with one of said chambers, a heat generating burner, a pilot 25 burner and an object to be heated.

In testimony that I claim the foregoing as my invention, I have signed my name in presence of two witnesses, this 27th day of April 1915.

JOSEPH ALEXANDER MAYERS.
